US0D1064548S

(12) **United States Design Patent** (10) **Patent No.:** **US D1,064,548 S**
(45) **Date of Patent:** **** Mar. 4, 2025**

(54) **SNEAKER**

(71) Applicant: **ROTHY'S, INC.**, San Francisco, CA (US)

(72) Inventors: **La Vion Gibson**, San Francisco, CA (US); **William Roth Martin**, San Francisco, CA (US)

(73) Assignee: **ROTHY'S, INC.**, San Francisco, CA (US)

(**) Term: **15 Years**

(21) Appl. No.: **29/876,990**

(22) Filed: **May 31, 2023**

Related U.S. Application Data

(63) Continuation of application No. 29/740,617, filed on Jul. 6, 2020, now Pat. No. Des. 991,637.

(51) **LOC (15) Cl.** **02-04**

(52) **U.S. Cl.**

USPC **D2/969**; D2/973

(58) **Field of Classification Search**

USPC D2/902–908, 920, 969–974

CPC .. A43B 1/009; A43B 1/02; A43B 1/04; A43B 5/00; A43B 5/02; A43B 5/06; A43B 5/10

See application file for complete search history.

(74) *Attorney, Agent, or Firm* — ArentFox Schiff LLP

(57) **CLAIM**

The ornamental design for a sneaker, as shown and described.

DESCRIPTION

FIG. 1 is a right perspective view of a sneaker showing our new design;

FIG. 2 is front view of the sneaker shown in FIG. 1;

FIG. 3 is a rear view of the sneaker shown in FIG. 1;

FIG. 4 is a right side view of the sneaker shown in FIG. 1;

FIG. 5 is a left side view of the sneaker shown in FIG. 1;

FIG. 6 is a top view of the sneaker shown in FIG. 1; and,

FIG. 7 is a bottom view of the sneaker shown in FIG. 1. The broken lines represent portions of the sneaker that form no part of the claimed design.

1 Claim, 7 Drawing Sheets
